(57) **CLAIM**

The ornamental design for a vision assessment chart, as shown and described.

DESCRIPTION

FIG. 1 is a symmetrical front view of a vision assessment chart showing our new design according to a first embodiment;

FIG. 2 is an enlarged view of portion 2 of FIG. 1;

FIG. 3 is an enlarged view of portion 3 of FIG. 1;

FIG. 4 is an enlarged view of portion 4 of FIG. 1;

FIG. 5 is a side view of the vision assessment chart of FIG. 1, where all other side views are identical;

FIG. 6 is a symmetrical front view of a vision assessment chart showing our new design according to a second embodiment;

FIG. 7 is an enlarged view of portion 7 of FIG. 6;

FIG. 8 is an enlarged view of portion 8 of FIG. 6;

FIG. 9 is an enlarged view of portion 9 of FIG. 6; and,

FIG. 10 is a side view of the vision assessment chart of FIG. 6, where all other side views are identical.

The broken lines show environment and form no part of the claimed design. Color is claimed in FIGS. 1, 2, 3 and 4, with the color green claimed in FIG. 2, the color yellow claimed in FIG. 3, and the color red claimed in FIG. 4. Color is not claimed in FIGS. 6, 7, 8 and 9. Text and lead lines are not claimed in FIGS. 1 and 6.

1 Claim, 2 Drawing Sheets
